UNITED STATES PATENT OFFICE

2,434,436

TOY MACHINE GUN

Harold S. Rochowiak, Detroit, Mich.

Application June 22, 1944, Serial No. 541,501

1 Claim. (Cl. 124—27)

1

The present invention relates to improvements in mechanical toy guns.

The primary object of the invention is to provide a toy gun which is economical in construction, simple in operation and resembles a repeating machine gun in appearance and shape.

Another object of the invention is to provide a toy mechanical gun in which the projectiles are fed from a magazine disposed above the barrel so as to be successively brought into position in front of a reciprocating spring-loaded plunger so as to project the projectiles one after the other.

Another object of the invention is to provide a toy automatic gun having an operator which can be manually rotated so as to successively retract the plunger against the action of the coil spring in quick succession.

Another object of the invention is to provide a mechanical toy gun of the above-mentioned character which is uniquely constructed with the various parts arranged to facilitate mass production and enhance the commercial success of the device.

Other objects and advantages will become apparent during the course of the following description of the accompanying drawing, wherein:

Figure 1 is a side elevational view of the mechanical toy gun embodying the invention illustrating portions thereof broken away to show various details of construction;

Figure 2 is a top plan view of the mechanical gun further showing the arrangement of the various parts thereof;

Figure 3 is a vertical cross sectional view taken on line 3—3 of Figure 1 looking in the direction of the arrows and illustrating the rotary operator for retracting the plunger against the tension of the spring; and

Figure 4 is a vertical cross sectional view taken on line 4—4 of Figure 1 looking in the direction of the arrows and illustrating various details of the magazine construction.

In the drawing, the reference character 5 will generally be employed to indicate a gun barrel of tubular construction formed of wood or the like and embodying a barrel section 6 having a longitudinal bore 7 extending from the muzzle end to the intermediate portion of said barrel. The bore 7 is enlarged as at 8 (Figure 1) to provide a recess or chamber for receiving a coil spring which will hereinafter be more fully described. Mounted in the rear end of the barrel 5 is a bushing 9 having a bore 10 axially aligned with the bore 7 and said bushing is fastened in place by means of a nail or the like as at 11.

Reciprocably mounted within the rear portion of the bore 7 and guided by the bore 10 of the sleeve 9 is a plunger 12 around which is encircled a coil spring 13 with one of its ends en-

2

gaging the sleeve 9 and its opposite end engaging a transverse pin 14 received in a suitable opening 15 in the reciprocating plunger 12. One end of the transverse pin 14 is slightly longer than the opposite end and projects radially into a longitudinal kerf slot 16 for being engaged by the rotary operator.

A radially extending elongated slot 17 is formed in the barrel section 6 at the rear end thereof and disposed within said slot is a channel shaped magazine for receiving a series of wooden projectiles or the like as at 19. The magazine 18 includes a rear wall 20 having side walls 21 terminating in inwardly directed opposed flanged portions 22 and 23 for engaging the rear and front portions of the projectile. It is noted that the magazine 18 is disposed slightly rearwardly of the inner end of the plunger 12 when the plunger is projected so that the same will engage the rear end of the projectile during its forward movement and project the same through the bore 7 of the barrel 5. Flanges 20a and 22a are formed in the rear wall 20 as well as the inwardly directed flanges 22 and 23 for receiving 15 nails or the like as at 20b and 22b so as to rigidly secure the magazine in place on the barrel 5. The side walls 21 are extended to project into the longitudinal slot 17 a slight distance to further support the magazine and prevent displacement 20 thereof.

The rotary operator comprises a yoke member or handle structure 24 having a handle portion 25 and parallel bifurcated arm portions 26. The barrel section 6 is flattened as at 28 at diametrically opposite sides thereof for receiving the bifurcated arms 26 and a nail or the like as at 29 is passed through one of the bifurcated arms 26 for anchoring the yoke member 24 in position.

Formed in the free ends of the bifurcated arms 30 26 is a pair of axially disposed and aligned bearing openings 30 for receiving the rotary shaft 31. One end of the rotary shaft 31 projects slightly beyond one of said bifurcated arms and is transversely bored for receiving a crank arm 33 having 35 a crank handle 34. The intermediate portion of the rotary shaft 31 is provided with radially extending bores 35 for receiving crossed pins 36 which are adapted to have their free ends successively brought into registry with the kerf slot 30 and into engagement with the transversely extending pin 14.

Formed in the rear portion of the barrel 5 is a longitudinal slot 38 which terminates at the rear end of the barrel and extends from a point 55 slightly rearward of the yoke member 24 and said slot is of sufficient width for receiving a gun stock 39 which is cut away as at 40 to conform to the shape of the shoulder. The gun stock may be fastened in the slot 38 by nails or the like or 60 other fastening means.

In operation, the stock 39 is placed against the shoulder and the handle 25 grasped by the left hand so that the right hand will be free to manipulate the hand crank 34 which is rotated to cause the radially projecting pins 36 to engage the transversely extending pins 14 on the reciprocating plunger 12 and thereby retract the plunger against the action of the coil spring 13. When the plunger 12 has reached the limit of its rearward movement, a projectile 19 will fall by gravity into the gun barrel bore 7 in the path of said plunger. As each of the pins 36 passes over the radially extending pin 14 when the plunger has reached the limit of its rearward travel, the reciprocating plunger 12 is projected forwardly to engage the rear end of one of the projectiles 19 which has fallen by gravity into the barrel bore 7 and thereby project said projectile 19 in the direction in which the toy mechanical gun is aimed.

It is to be understood that the form of the invention herewith shown and described is to be taken as a preferred embodiment of the same and that various changes may be made in the shape, size and arrangement of parts without departing from the spirit of the invention or the scope of the subjoined claim.

What I claim is:

A mechanical gun, comprising a barrel member having a longitudinal bore terminating at one end in an enlarged bore portion, a sleeve for be-

ing inserted in the enlarged bore, a plunger mounted in said enlarged bore with one end guided in said sleeve and the other end projecting into and guided in said longitudinal barrel bore, a handle structure secured to the barrel having forked arms projecting above said barrel and a handle projecting downward below said barrel, a rotary tripping member mounted between said forked arms and journaled therein, said tripping member engaging and releasably retracting said plunger, and a coil spring engaging and urging said plunger toward said tripping member.

HAROLD S. ROCHOWIAK.
